UNITED STATES PATENT OFFICE.

JOHN MCPHAIL, OF LIVERPOOL, COUNTY OF LANCASTER, ENGLAND.

SPECTACLES.

SPECIFICATION forming part of Letters Patent No. 416,485, dated December 3, 1889.

Application filed July 30, 1889. Serial No. 319,160. (No model.)

To all whom it may concern:

Be it known that I, JOHN MCPHAIL, a subject of the Queen of Great Britain and Ireland, residing at Liverpool, in the county of Lancaster, England, have invented new and useful improvements in and connected with Spectacles, Eyeglasses, and Pince-Nez, of which the following is a specification.

According to my invention there is provided

10 an elastic bearing on that part of the frame of spectacles, eyeglasses, or pince-nez that grips or rests on the nose of the user. This elastic bearing is of such a nature that it will adapt itself to the contour of the nose and will give

15 a larger bearing-surface than the ordinary plaque. For the above purpose I employ a flat spirally-coiled wire having milled edges and so connected to each side of the frame of the glasses as to form an elastic bearing which

20 will adapt itself to the contour of the nose of the user.

The accompanying drawings, which make a part of this specification, serve to illustrate my invention.

25 The drawings are marked with letters of reference corresponding with those used in the following explanation, and like letters are used to denote like or corresponding parts throughout the several figures.

30 In the drawings, Figure 1 is an elevation of a pair of eyeglasses or pince-nez with the improvements according to my invention applied thereto. This figure shows the normal state of the pince-nez before application to the

35 nose of the user. Fig. 2 shows the state of the pince-nez when on the nose of the user. Fig. 3 is an enlarged view of a portion of the eyeglass or pince-nez with my improvements applied thereto. Fig. 4 is an end-view of the

40 spirally-coiled wire which forms the bearing or plaque for the nose. Fig. 5 is an enlarged view illustrating the construction of the spirally-coiled wire. Fig. 6 is an end view of the wire coil. Fig. 7 is an enlarged section of the

45 wire. Figs. 8 and 9 illustrate in a normal and extended state, respectively, the application of my invention to pince-nez having a straight expanding bridge and hinged adjustable nose-bearings or plaques.

50 It will be seen that Figs. 1, 2, 8, and 9 of the drawings illustrate known forms of eye-

glasses or pince-nez with my improvements applied thereto.

According to my invention I make the bearing or plaque of an elastic medium, as illustrated at *a*, Figs. 1 and 2, so that when in position on the nose it will yield, as shown at *a'*, Fig. 2. To provide the spiral-wire coil with a gripping-surface it is drawn with the section shown at Fig. 7—namely, with a hollowed-out face having projecting edges *b*. These edges *b* are then milled, and thus a rough surface is formed on the outside of the wire. The wire is then coiled on a mandrel into the form shown at Figs. 5 and 6. To attach the spiral coil to the frame I provide the usual brackets *c c*, with short flat springs *d d*. These springs *d d* enter and slip between the coils of the wire, as illustrated in Figs. 3 and 4. These springs *d d* keep the spiral coil in its place and prevent side motion. The spiral wire is attached to the springs *d d* by passing the ends of the wire through holes *e* in the springs *d d*, as shown at Fig. 4. The spiral coil is by preference made of gold or silver wire, or a metal or alloy that will not readily tarnish.

The spiral coiled wire plaques *a*, above described, can be applied to any form of folding or rigid eyeglasses, spectacles, or pince-nez which adhere to the nose by friction and spring. For example, they can be applied to the form of eyeglasses shown at Figs. 8 and 9. In this case the plaques are hinged to the frame of the glasses and the coiled wire is attached to the plaques by the springs *d d*. The normal form of the coiled wire is shown at Fig. 8, and Fig. 9 shows the form taken by the coiled wire when the eyeglasses are in use on the nose of the wearer.

In the foregoing description of my invention I have described its application more particularly to that type of eyeglasses which are kept on the nose by the action of a spring-bridge; but I would have it understood that my invention is also applicable to other types of eyeglasses, such as spectacles in which the bridge or connecting-bar rests on the nose of the user. In this case the frame which contains the glasses can be provided with the spiral coiled wire plaques *a*, as above described in reference to Figs. 1 and 2, or a secondary bridge consisting of a spiral coiled wire can

be added under the main bridge or connecting-bar. This secondary bridge is connected at each end to the frame of the glasses and forms an elastic pad, which rests on the nose of the user and takes the weight of the spectacles.

5 Although I have described a coiled wire as the best medium of which to make the elastic bearings or plaques, I would have it understood that other elastic medium may be used.

10 By the use of elastic bearings or plaques, above described and according to my invention, a much lighter pinching-spring can be used, and thereby the weight of the eyeglasses is reduced, and the pinch on the nose of the 15 user is lessened; also, by the use of the elastic bearing or plaques *a* the pressure is spread over the greatest possible surface of the nose consistent with neatness of form.

Having now particularly described and ascertained the nature of my said invention, and in what manner the same is to be performed, I declare that what I claim is—

1. In spectacles, eyeglasses, and pince-nez, the combination, with the frame, of an elastic

nose-bearing consisting of coiled wire *a*, provided with milled edges *b*, substantially as described.

2. In spectacles, eyeglasses, and pince-nez, the combination, with the frame thereof, of an elastic nose-bearing comprising the spirally-coiled wires *a*, having milled edges *b* and retaining-springs *d*, substantially as and for the use and purposes shown and described.

3. In spectacles, eyeglasses, and pince-nez having hinged adjustable nose-bearings, as described, the combination, with said hinged bearings, of spirally-coiled wires *a*, having milled edges *b* and retaining-springs *d*, substantially as and for the use and purposes shown and described.

40 In testimony whereof I affix my signature in presence of two witnesses.

JOHN MCPHAIL.
